US0D1020368S

(12) **United States Design Patent** (10) **Patent No.:** **US D1,020,368 S**
(45) **Date of Patent:** **** Apr. 2, 2024**

(54) **FOOD PROCESSOR**

(71) Applicant: **WHIRLPOOL CORPORATION**,
Benton Harbor, MI (US)

(72) Inventors: **John W. McConnell**, St. Joseph, MI
(US); **Yifan Wang**, St. Joseph, MI
(US); **Wenkai Wu**, Aurora, IL (US)

(73) Assignee: **WHIRLPOOL CORPORATION**,
Benton Harbor, MI (US)

(**) Term: **15 Years**

(21) Appl. No.: **29/881,645**

(22) Filed: **Jan. 4, 2023**

Related U.S. Application Data

(63) Continuation of application No. 29/781,065, filed on
Apr. 28, 2021, now Pat. No. Des. 977,901, which is
a continuation of application No. 29/682,098, filed on
Mar. 1, 2019, now Pat. No. Des. 920,032.

(57)

CLAIM

The ornamental design for a food processor, as shown and described.

DESCRIPTION

FIG. 1 is a perspective view of a food processor according to the design;

FIG. 2 is a front elevation view thereof;

FIG. 3 is a back elevation view thereof;

FIG. 4 is a left side elevation view thereof;

FIG. 5 is a right side elevation view thereof;

FIG. 6 is a top plan view thereof; and,

FIG. 7 is a bottom plan view thereof.

(Continued)

The portions of the food processor shown in broken line form no part of the claimed design.

1 Claim, 7 Drawing Sheets
